FUR CLIPPING MACHINE

Freeman Knowles, Northville, N. Y., assignor of
one-half to Walker La Rowe, Northville, N. Y.

Application October 5, 1936, Serial No. 104,102

1 Claim. (Cl. 149—26)

My invention relates generally to means for clipping and trimming furs, and an important object of the invention is to provide means whereby the fur skins are exactly held while being carried past a set of revolving knives which clip the hair to any set length, whereby complete and accurate trimming of the skin is achieved in one operation, wherein the hair over the entire length and width of the skin is uniformly clipped.

10 Another important object of my invention is to provide a simple and practical arrangement of this character which does not require extensive handling of the skins, and which can be operated by unskilled persons.

15 Other important objects of my invention will be apparent from a reading of the following description taken in connection with the drawings, wherein for purposes of illustration I have shown preferred embodiments of my invention.

20 In the drawings:

Figure 1 has a right hand elevational view of an embodiment of the invention.

Figure 2 is a back view of Figure 1 taken looking from right to left in Figure 1 with the cutter removed.

Figure 3 is a longitudinal vertical sectional view taken through Figure 1 the section being taken on approximately the line 3—3 of Figure 1.

Figure 4 is a transverse vertical sectional view taken through Figure 2 the section being taken on approximately the line 4—4 of Figure 2.

Figure 5 is a transverse vertical sectional view taken through another embodiment of my invention.

35 In the drawings, and referring first to the embodiment of the invention shown in Figures 1 through 4, the numeral 5 generally designates a suitable support on which are mounted two end plates 6 which are annular in form and have 40 radially extending lugs 7 which act as journals for the various roller shafts to be described. The annuli 6 receive therethrough the suction pipe 8 which at a point between the plates 6 has tangentially flaring sides 9 and 10 which define a 45 suction opening therebetween facing the back of the machine.

Journalized in the respective lugs 7 are the upper and lower roller shafts 11 and 12, and the front and back roller shafts 13 and 14, the shaft 11 50 having a surrounding roller 11', the shaft 12 a roller 12', the shaft 13 a roller 13' and the shaft 14 a roller 14', all of which rollers engage the inner side of a cylindrical casing 15 which is revoluble by reason of this arrangement and has 55 over its surface the perforations 16 a portion of

which are adapted to register with the opening defined by the suction pipe flanges 9 and 10 as they come into registry therewith. The shaft 13 extended beyond its supporting lug 7 and has a pulley 17 thereon which may be driven by a suitable belt (not shown) for revolving the cylinder 15 at the required rate of speed.

Having their opposite ends journaled in spaced members of the support 5 are roller shafts 18, 19 and 20 which have trained thereover the belt 10 21 whose upper flight 22 is conformed to and runs against the bottom of the revolving cylinder 15 as clearly shown in Figures 1 and 4.

Vertical projections 23 on the respective plates 6 mounted L-shaped brackets 24 which are pivoted as indicated by the numeral 25 to the projections and carry at their outer ends or front ends the shaft 26 which mounts a heavy roller 27 over which is trained a belt 28 whose lower flight 29 conforms to and rides upon and is driven by contact with the surface of the upper part of the revoluble drum 15. Another shaft 30 is supported at its opposite ends by arms 31 pivoted as indicated by the numeral 32 to the back part of the projections 23 and carries a smaller roller 33 over 25 which the belt 28 also is trained. In addition the arms 31 have mounted thereon the beam 34 to which are attached and from which depend the pressure fingers 35 which engage the back part of the cylinder 15 as clearly shown in Figures 1 30 and 4 and also in Figure 2.

The remaining arms of the L-shaped levers 24 have mounted thereon the shaft 36 which contains the roller 37. The shaft 36 is mounted in a slide bearing arrangement 38 on each of the 35 arms of the levers 24 which by reason of which a screw arrangement 39 is adjustable to different positions to ride against the upper flight 40 of the belt 28.

A contracting spring 41 is stretched between 40 the lower arm of each of the levers 24 and each of the projections 23 as indicated in Figure 1 to tension the roller 27 and its belt 28 against the upper part of the revolving cylinder 15. A second tensioning spring 42 is stretched between the 45 roller part of each arm 31 and each of the projections 23 as illustrated in Figure 1 for tensioning the roller 33 against the upper back part of the revolving cylinder and in addition to tension the spring fingers 35 against the back of the revolving cylinder.

Mounted on the support 5 immediately to the rear of the revolving cylinder 15 is the cutter cylinder 43 which is mounted on a rotary shaft 44 and is shielded by a shield 45. The cutter 55

cylinder has conventional cutters 46 arranged circumferentially thereof and in shearing relation to a stationary cutter 47 which lies in an approximately perpendicular plane and spaced 5 below the lower ends of the flexible fingers 35 as illustrated in Figure 4. Suction is present in the housing 43 in a conventional manner to draw the loose ends of the hair of the skin between the cutters.

10 The skin is fed over the front upper part of the revolving drum 16 so that the belt 28 tensions the same against the upper part of the cylinder and acts to make the same engage the cylinder evenly throughout the length and width thereof, 15 the skin being engaged by the lower flight 29 of the belt, and the belt holds the skin in engagement with the cylinder 15 until the cylinder with the skin thus held thereon turns to a point where the perforations 16 register with the opening in 20 the suction pipe, whereupon the suction in the suction pipe will strongly and evenly secure the skin to the exterior of the cylinder so that all uneven edges will be exactly held. The skin and all parts thereof thus held against the exterior 25 of the cylinder by suction, is carried down under the tensioning fingers 35 until exactly in a position to have the fur thereof clipped by the cooperating knives 46 and 47.

The arrangements are such that as the leading 30 edge of the skin passes the region of the clipping, the same will engage between the belt 21 and the lower part of the cylinder and pass from the region of the suction opening to the bottom of the cylinder, the exact positioning 35 of the skin being maintained by the portion of the skin which is over the suction hole and that portion of the skin preceding the same which is held in place on the cylinder by the belt 21; whereby the skin, throughout its operative engagement with the cylinder 15, is held 40 in an exact, smooth, and even contact with the drum, so that absolutely uniform clipping of the hair thereof throughout the length and width of the skin is accomplished by passing the same once through the machine. The position of the 45 stationary knife 47 and of the revoluble knives 46 may be altered to achieve the cutting of the hair of the skin at the desired length.

In Figure 5 of the drawings another embodiment of the invention is shown and comprises 50 a large revoluble cylinder 50 which has trained thereover a perforated belt 51 which has a horizontal flight 52 which is the upper flight and an angulated flight 53 which is the lower flight. The upper flight 52 is passed across the horizontal top 55 54 of a suction conduit 55 which has in its top an opening 56 whose presence causes the exertion of suction through the holes or perforations 57 in the belt 51. The conduit 55 is projected from the suction pipe 58 around which the belt 51 moves as indicated, and brackets 59 projecting from the conduit, carry spring fingers 60 which bear against the back of the belt passing around the pipe 58 as clearly shown in Figure 5 to guide 60 the skin past the fur cutting stationary knife 47 and the revolving knives 46, the latter being mounted on a shaft 44 which is driven from a suitable power source. An overlying shield 45 is provided for protecting the rotary cutter.

70 Engaging the right hand portion of the bottom

of the flight 53 of the perforated belt 51 is the upper flight 22' of the tensioning belt 21' which runs over a roller 20', a lower roller 19' and a front roller 18' corresponding to the similarly numbered rollers in the first described embodiment.

In the embodiment of the invention shown in Figure 5 the skin to be clipped is laid on the upper flight 52 of the belt back of the suction opening 56 and the belt carries the same along until the opening 56 is reached, whereupon suction is transmitted from the conduit 55 through the holes 57 in the belt to the skin, whereby the skin is positively evenly held on the belt and transported toward and into engagement with the spring fingers 60 which hold the same in the proper position for clipping of the hair thereof by the knives. As indicated by the numeral 61 the suction opening 56 extends down along the back of the suction pipe 58 so as to retain the suction effect for holding the skin until the same has passed the clipping position, and has engaged its forward edge with the flight 22' of the belt 21', which then mechanically holds the skin until the skin has passed the related position.

It is to be noted that neither the perforated cylinder 15 nor the perforated belt 51 has to be perforated over its entire width and length or circumference, but may be perforated only in such portions thereof as necessary to carry the leading edge of the skin past the clipping knives or cutters, the remainder of the skin being then held to the cylinder or belt by the spring pressure fingers 35. Where more than one type of work is to be done by one machine, shields of impervious material may be applied to a completely perforated cylinder or belt to close off the undesired perforations.

Although I have shown and described herein preferred embodiments of my invention, it is to be definitely understood that I do not desire to limit the application of the invention thereto, and any change or changes may be made in the materials, and in the structure and arrangement of the parts, within the spirit of the invention and the scope of the subjoined claim.

What is claimed is:

A machine for clipping the fur or hair or skins comprising a cylinder having perforations therein, means for rotating the cylinder, a suction chamber in the cylinder having an opening therein covered by a limited area of the inner circumferential part of the cylinder, means for creating a suction in the chamber, clipping means arranged adjacent that part of the cylinder which is passing over the opening, a supporting frame for the cylinder and clipping means, a pair of pivoted arms carried by the frame, a roller carried by said arms, a second pair of arms pivoted in the frame, a roller carried thereby, a belt carried by the rollers and having a portion contacting the cylinder in advance of the clipping means, spring means for holding the arms with the belt in engagement with the cylinder and spring fingers carried by the second pair of arms and engaging the cylinder at a point adjacent the point where the clipping means engage the fur or hair of the skins.

FREEMAN KNOWLES.
